UNITED STATES PATENT OFFICE.

WILLIAM HENRY HACKING, OF BURY, ENGLAND

CLOTH-FOLDING MACHINE.

No. 813,552.

Specification of Letters Patent.

Patented Feb. 27, 1906.

Application filed September 26, 1904. Serial No. 226,073.

To all whom it may concern:

Be it known that I, WILLIAM HENRY HACKING, a subject of the King of Great Britain and Ireland, and a resident of California Iron Works, Bury, Lancaster county, England, have invented a certain new and useful Cloth-Folding Machine, (for which I have filed application for British Patent, No. 13,701, dated June 17, A. D. 1904;) and I do hereby declare the following to be a full, clear, and exact description of the invention, such as will enable others skilled in the art to which it appertains to make and use the same.

15 The present invention relates to an improved machine for folding or laying cloth in a pile of folds each of which is of a predetermined length.

Broadly, the two main elements of the invention consist in, first, an improved table constructed so as to form a concave support for the pile of cloth. The degree of concavity is readily variable to suit different kinds of cloth. The second main element consists in 25 a novel combination of mechanism for operating the blades which convey the cloth from side to side and form the folds. These two main elements working in conjunction and with the aid of the adjustments provided for 30 insuring their efficient coöperation enable folds of cloth of the most varied kinds to be laid in a pile on the table of the machine with much greater precision as regards the lengths of the individual folds in the pile than has 35 hitherto been possible. The details of these main elements and of the adjustments provided for regulating their action are herein-after described with reference to the accompanying drawings, in which—

40 Figure I is a side elevation. Fig. II is a detached elevation of the table. Fig. III is a detached elevation of the blade-tilting gear. Figs. IV^a, IV^b, and IV^c are diagrams illustrating the positions of the mechanism which 45 operates the folding-blades at the ends and at the middle of the stroke.

Referring first to the table, this is divided into two or more parts. In the illustration it consists of two leaves 1 and 1^a, resting on hinge-pins 2 and 2^a in the table-carrier 3.

As is usual in cloth-folding machines of the general type to which this machine belongs the cloth *c*, Fig. I, is carried from side to side of the machine by blades which form 55 it into folds and insert the folds under clamps

4. The latter rise alternately for the admission of the fold of cloth and on their descent clamp the pile of folded cloth to the table.

When a pile of cloth is thus laid on a flat 60 table, the pressure of the clamps at the sides compresses the cloth there in such a manner that the pile of cloth as a whole is thinner at the sides than at the middle of the pile where the pile of cloth is free from external pressure. Hence as the pile increases in thickness it acquires a saddle-back shape of gradually-increasing curvature. The consequence is that as the successive folds of cloth are superposed on those already laid they gradually 70 become longer, owing to the greater length of the reach from side to side, (measured along the curved surface of the pile as compared with the rectilinear distance.) In practice this known defect is to some extent 75 compensated for by so determining the length of the folds that the average length shall equal the nominal length of the folds, which, however, vary among themselves. Such variation of the length of the individual folds 80 depends on the nature and the elasticity of the cloth and is in some cases very great. Another disadvantage of this arching or thickening of the pile of cloth is that it presents an obstacle to the employment of folding-blades traveling in a rectilinear path such as it is desirable to use in order to obtain the greatest possible accuracy in the length of the individual folds of a piece. According to the present invention this arching 85 of the pile as it grows is compensated for by the use of the concave table 1 1^a. The folds are stretched across the chord of the concavity and are laid under the clamps in a rectilinear line while the fold is being made. 90 After being made at the alternate rise of each clamp the folds are released and they sink by their own weight into the intervening concavity of the table. The amount of compensation to suit cloth of different natures is varied by raising or lowering the leaves of the table, and thus altering the degree of concavity. This may be effected in various ways, as by screws, sliding wedges, or the like. In 95 practice I find it most convenient to support the leaves of the table on rotatable eccentric or polygonal supports 5 5^a. Since about five variations of concavity practically cover the whole range in ordinary work, I use pentagonal supports, as shown in the drawings. 100 The sides of the pentagon are at different distances from the axis of rotation 6 of the sup-

100

105

110

port. By turning the supports round, so as to cause the leaves of the table to rest on any of the sides of the support, any desired tilt may be given to the leaves of the table.

5 The table-carrier 3 is mounted in vertical guideways and is normally pushed upward, so that the pile of cloth bears against the clamps by a weighted lever or spring in the usual manner. In the example shown in the 10 drawings the upward pressure of the table is obtained from a spiral spring 7 (one end of which is attached to a fixed part of the machine-frame) pulling against a chain 8 on a curved lever 9, having a fixed fulcrum at 10. 15 A chain 11, secured to the table-carrier and to a second curved lever 12, which rotates with the curved lever 9, causes the pulling action of the spring 7 to lift the table.

The table is depressed against the pull of 20 the spring by a treadle-lever 13, connected by a link 14 to the curved lever 9. A swinging catch 15 is fulcrumed to the treadle itself, and when the latter descends the catch 15 automatically takes under a detent 16 and prevents the return of the table until released. 25 Being combined with the treadle itself the detent is released by the foot of the attendant when on the treadle and in a position to fully control the rising of the table, thereby preventing such shock and damage to the machine as is liable to occur when a separate 30 detent or catch operated by hand is used.

The clamps 4 4^a, Fig. I, as is usual in machines of this class, are alternately and intermittently lifted to permit insertion of the successive folds of cloth on which they bear. These clamps are operated by eccentrics or cams 17, deriving motion by means of a cam-shaft and bevel-wheels from the main driving-shaft, as shown in Fig. 1. I do not herein claim such clamp-operating means by themselves, and hence have not thought it necessary to explain them more in detail. The clamps 4 4^a and their lifting mechanism may 40 be set at different distances apart by means of a screw-shaft engaging in nuts carried by the parts which support the clamps.

The second main element of the invention consists, as hereinbefore stated, in the mechanism for operating the folding-blades 18 18^a. 50 When just inserting a fold of cloth under the left-hand clamp 4, the acting folding-blade 18^a is horizontal. (Fig. IV^a.) At the return stroke the blade 18^a rises, and the other folding-blade 18 takes charge of the cloth, Fig. IV^b, and finally descends and inserts the cloth under the right-hand clamp 4^a, Fig. IV^c. These functions and changes of position of the folding-blades are common to all machines of this general type and of themselves 55 form no part of my present invention.

The folding-blades 18 18^a are at each end mounted on and secured to an oscillating trough-shaped carrier 19, which carries (or is 60 preferably cast integral with) a toothed seg-

70 ment 20. The carrier 19 and the toothed segment 20 are journaled at 21 at the extreme end of the side arm 25. On the side arm 25 is also journaled at 24 a segment 22, having internal teeth 23, which extend over and engage with the teeth of the toothed segment 20. The side arm 25 is journaled on a stud or block 27, which is free to slide up and down in the slot 28 and is also hinged at 29 to a radius-rod 30, having a stationary fulcrum at 31 on the machine-frame. As the side arm 25 swings about its fulcrum 26 it carries the folding-blades from side to side, and owing to the constraint of the radius-rod 30, in combination with the rising and falling fulcrum 26, 80 the folding-blades have a rectilinear path.

85 The whole of the movements of the folding-blade are derived from the crank 32. The latter is driven by gear-wheels indicated by dotted lines at 33 and 34 from the main driving-shaft 35. The crank-pin 36 is mounted in a slot 37 in the crank, and by means of an adjusting-screw lying therein the stroke of the crank may be varied to suit different widths of fold. The crank-pin 36 engages 90 with a transverse slot 38 of the connecting-rod 39. The latter is hinged at one end at 29 to the side arm 25 and to the radius-rod 30 and at the other end is hinged at 40 to a second radius-rod 41, having a stationary fulcrum at 42 on the machine-frame. The radius-rods 30 and 41 are of equal length and parallel to each other and suspend and guide the connecting-rod 39 and the side arm 25, while the blade-carrier 19 moves from side to 95 side of the machine under the action of the crank, so that the parts occupy the successive positions indicated by the diagrams in Figs. IV^a, IV^b, and IV^c. The segment 22 has an arm 43 hinged at 44 to a rod 45. (Herein referred to as the controlling-rod.) The latter is fulcrumed on a stud 46, which can be secured at any desired point on a curved slot 47, formed in the connecting-rod 39.

100 As will be seen from a comparison of Figs. IV^a, IV^b, and IV^c, the internally-toothed segment 22 maintains approximately a horizontal position from end to end of the stroke. The center 21 of the toothed segment 20, however, is carried by the angular nature of the movement of the side arm relatively around the center 24 of the internally-toothed segment 22 for a portion of a revolution, and so obtains from its contact with the teeth thereof an angular displacement approximately sufficient for the purpose required. Since, however, the same angular displacement must be given to the toothed segment 20 for short strokes as well as for long strokes, some means of compensating for varying lengths of strokes, 115 so as to obtain a constant displacement, is necessitated. This is provided for by carrying the stud 46 in the curved slot 47. The ratio of gearing of the segments 20 and 22 is so arranged that when the machine is making 120 125 130

5 folds of maximum length the requisite angular displacement of the segment 20 is obtained by securing the stud 46 at such a point of the slot 47 that the controlling-rod 45 and the side arm 25 are parallel, and the internally-toothed segment 22 thereby also parallel to the connecting-rod 39—that is to say, horizontal throughout its stroke. In order to obtain the same displacement from shorter 10 folds than these, the slot which carries the stud 46 is prolonged away from the side arm 25 in a path which is an arc of a circle the radius of which is equal to the length of the radius-rod 30 and which has as its center the 15 upper axis 31 of the radius-rod 30 when the side arm 25 is in the mid-position. (Shown in Fig. IV^b.)

10 To obtain the required angular displacement of the toothed segment 20 when the machine is making its shortest strokes, the stud 46 is secured at the end of slot 47 farthest away from the side arm 25. The rod 45 and the side arm 25 being then out of parallel, the arm 43 of the internally-toothed 20 segment does not keep a horizontal position, but is alternately moved up and down in such a manner as to give the required additional movement to the toothed segment 20. The requisite additional movement for all intermediate lengths of stroke may be obtained 30 by securing the stud 46 at intermediate points of the slot 47.

35 In like manner by correspondingly varying the concavity of the table to suit altered conditions of stroke (for the same material) or to suit various kinds of cloth for the same stroke the cloth as it is laid will follow the rectilinear path of the folding-blade, and thus the greatest precision and uniformity in the 40 width of the individual folds of the pile is obtained.

45 The transverse slot 38 in the connecting-rod 39 is important as providing a means for overcoming a defect hitherto existing in all plaiting-machines having a side arm, such as 25, driven by a crank.

50 The clamps 4 and 4^a have a uniform motion and always descend at the same relative times whether the side arm is making a long or a short swing. If the machine is only used for folds of one size, the descent of the clamps 4 4^a can be easily timed so as to descend just at the proper moment when the folding-blades insert the cloth. If, however, 55 the throw of the crank is altered to give, say, a longer stroke, (while the connecting-rod remains the same length,) the side arm will not be at its mid-position when the crank-pin is at mid-stroke, and consequently the arrival 60 of the folding-blades at the ends of the stroke will no longer synchronize with the descent of the clamps. This defect could be remedied by adjusting the length of the connecting-rod for each separate length of fold, 65 lengthening it for long folds and shortening

it for short folds. Such a procedure is, however, troublesome. By the use of the transverse slot 38 an automatic compensation is provided which overcomes this defect in such a way that the side arm 25 is always in its 70 mid-position when the crank is in the middle of its stroke, and consequently the arrival of the folding-blades at each end of their stroke synchronizes with the movements of the clamps whatever may be the throw of the 75 crank.

It is to be understood that, although only one side of the machine is shown in the drawings, the mechanism for operating the folding-blades is symmetrically applied on both 80 sides of the machine.

What I claim as my invention, and desire to secure by Letters Patent, is—

1. In a cloth-folding machine the combination of alternately-acting clamps means for 85 operating them a table normally pressed upward against said clamps reciprocating folding-blades an oscillating carrier for said blades means for oscillating said carrier about its axis in a side arm a side arm having a rising and falling fulcrum a connecting-rod having a transverse slot a crank engaging with said slot and two parallel radius-rods suspending and supporting said connecting-rod and side arm substantially as and for the purpose set forth and shown. 90

2. In a cloth-folding machine the combination of alternately-acting clamps means for operating them a table normally pressed upward against said clamps a reciprocating 100 side arm a crank and connecting-rod for operating said side arm an oscillating blade-carrier journaled in said side arm a toothed segment concentric therewith a toothed segment eccentric thereto engaging with the concentric segment and a controlling-rod between said eccentric segment and the connecting-rod and having a variable point of attachment to the latter substantially as and for the purpose set forth and shown. 105

3. In a cloth-folding machine the combination of cloth-folding blades mounted in a carrier on a side arm, means for oscillating said carrier and imparting a reciprocating rectilinear motion thereto from side to side, 115 alternately-acting clamps and means for operating them, a table having leaves hinged or so mounted that they can be raised or lowered so as to form a table of variable concavity, supports by which the leaves are maintained in their various positions of adjustment independent of the means for pressing the table upward against said clamps substantially as and for the purpose set forth. 120

4. In a cloth-folding machine, the combination of cloth-folding blades, mounted in a carrier on a side arm, with means for oscillating and reciprocating the said carrier, a table having leaves adapted to be independently tilted, rotatable supporting devices arranged 125

under the said leaves individually and each having operative faces at varying radial distances from its axis, for adjusting the inclination of said leaves and holding each leaf in 5 the position to which it is thus adjusted, clamps acting alternately on the cloth which is supported by the said table, means for actuating the said clamps and means for nor-

mally bringing the said table and clamps together substantially as set forth.

In witness whereof I have hereunto set my hand in the presence of two witnesses.

WILLIAM HENRY HACKING.
